Inventor:

Theodor Röghmanns

UNITED STATES PATENT OFFICE.

THEODOR ROGHMANNS, OF SONSBECK, GERMANY.

MONORAIL RAILWAY WITH AEROPLANE CARS.

1,415,400.

Specification of Letters Patent.

Patented May 9, 1922.

Application filed June 30, 1920. Serial No. 393,217.

(GRANTED UNDER THE PROVISIONS OF THE ACT OF MARCH 3, 1921, 41 STAT. L., 1313.)

To all whom it may concern:

Be it known that I, THEODOR ROGHMANNS, a citizen of the German Republic, and residing at Sonsbeck, Germany, have 5 invented certain new and useful Improvements in Monorail Railway with Aeroplane Cars, (for which I have filed an application in Germany Mar. 1, 1918, Patent #334,361,) of which the following is a specification.

10 The invention refers to a mono-rail railway, the cars of which are equipped with supporting and equilibrium planes similar to those of a flying machine and by means of these planes the car is kept in complete balance while running along the mono-rail, the track being at the same time relieved from the weight of the car.

15 The essential point of the invention is that the car body is vertically movable with 20 in certain limits and connected to the motor-driven carriage. The fore carrying or driving wheel is a toothed wheel, which is permanently geared to the rigid toothed track.

25 Owing to this arrangement a sufficient adhesion between driving wheel and track—necessary for a satisfactory service—as well as a high speed are obtained and in addition the track will be relieved by the lifting power of the air which circumstance 30 allows the track and its substructure to be made lighter. The favourable distribution of the weight of the car and its load will prevent the running car from skidding.

35 Fig. 1 of the drawing is a perspective view of the new railway, Fig. 2 is a longitudinal section and Fig. 3 is a cross section on line A—B.

40 The car hanging down on either side of the track (a) is built in such a way that its centre of gravity lies deeper than the upper edge of the track. The car body (e) which preferably at its upper sides or lower sides bears supporting and balancing planes (b, c, d), is equipped at its inner sides with 45 vertical guides (f) sliding in which are corresponding guide bars (g) of the carriage (s), this latter being equipped with the driving motors (h) and with the two carrying wheels (i, i¹) arranged one behind 50 the other, the fore wheel (i) being driven by the motors (h). The displacement of the car body (e) on the carriage is limited

by suitable means such as loose chains (k) connecting said car body to the carriage, so that the car body (e) owing to the buoyancy produced whilst running at a normal speed, can move only to a certain extent upwards, any further upward move being prevented by the weight of the carriage.

55 The carriage is equipped with arms (l) reaching with their hook-shaped ends (m) under the track, whereby the carriage is hindered from lifting off the track when running at a high speed.

60 The carrying wheel (i) of the carriage is a toothed wheel having teeth (n) at either sides of its tread. At suitable distances pins (o) are arranged on both sides of the rail, to which the teeth of the toothed carrying wheel will gear when the car is 65 moving along. Even when the car body is a little lifted, the carrying wheels will not 70 slip on the track.

75 The teeth of the carrying wheel (i) as well as the corresponding part of the rail to which said teeth will gear, may be of any suitable form, the essential point being only that both parts will gear into each other like teeth, thus preventing the wheel's slipping. The car body may also be of any suitable 80 form and accommodated for passengers or goods.

85 The motors (h) may be driven by any fuel or by electricity led to the motors in any suitable way.

I claim:

1. Mono-rail railway having aeroplane cars, consisting of a track, a carriage with carrying wheels on said track, a box-shaped car vertically movable on said carriage, flying and supporting planes attached to the box-shaped car.

90 2. Mono-rail railway having aeroplane cars, consisting of a carriage with carrying wheels, a rail with toothed-shaped means, toothed-shaped pins in one of the carrying wheels, a motor for driving the toothed wheel, a box-shaped room vertically movable on the carriage, means for limiting the lifting movement of said box-shaped room, 95 supporting and flying planes fastened to said box-shaped room.

100 3. Mono-rail railway having aeroplane cars, consisting of a carriage with carrying

wheels, a rail for said carrying wheels, toothed-shaped means on said rail, toothed-shaped pins on the carrying wheel destined to gear to the toothed-shaped means of the rail, driving means for this toothed carrying wheel, a box-shaped room vertically movable on the carriage, means for limiting

the movement of the box-shaped room, flying and supporting planes fastened to said box-shaped room, means on the carriage 10 preventing the lifting off the track, substantially as described.

In testimony whereof I affix signature.
THEODOR ROGHMANNNS.
